UNITED STATES PATENT OFFICE.

GEORGE E. DOWNE, OF CHICAGO, ILLINOIS, ASSIGNOR TO THE AMERICAN RADIATOR COMPANY, OF NEW JERSEY.

DESIGN FOR A FIRE-POT FOR HEATERS.

SPECIFICATION forming part of Design No. 33,388, dated October 16, 1900.

Application filed August 13, 1900. Serial No. 26,791. Term of patent 14 years.

To all whom it may concern:

Be it known that I, GEORGE E. DOWNE, a citizen of the United States of America, residing at Chicago, county of Cook, and State of Illinois, have invented and produced a new and original Design for Fire-Pots for Heaters, of which the following is a specification, reference being had to the accompanying drawings, forming a part thereof, and in which—

5 Figure 1 is a front elevation of the fire-pot. Fig. 2 is a vertical section on the line indicated by the arrows 2 2 of Fig. 1, and Fig. 3 is an inverted plan of the fire-pot.

10 As shown in the drawings, the leading or material features of the design consist of an annulus A, having inner and outer and end walls and being substantially cylindrical in form, but tapering slightly, however, from its lower end; an annular section B, occupying the

15 axis of the upper part of the member A and being open at its outer end and closed at its inner end, and radiating partitions C and D, each having top, bottom, and side walls and

connecting the member B with the member A. The wall of the member A has an oblong rectangular aperture located below the partition D.

25 Minor features of the design are an annular rib *a* at the upper end of the member A and adjacent to its outer surface, an annular rib *b*, projecting inwardly from the end of the member B, and the longitudinal fluting of the inner face of the member A from its lower end to the line of juncture of the partitions C with said wall.

30 35 I claim as my invention—

The design for a fire-pot for heaters, as herein shown and described.

In testimony whereof I have signed my name to this specification in the presence of two subscribing witnesses.

GEORGE E. DOWNE.
